UNITED STATES PATENT OFFICE.

THOMAS W. MILLER, OF ASHLAND, OHIO.

DESIGN FOR A BATHING-CAP.

45,015.

Specification for Design.

Patented Dec. 9, 1913.

Application filed June 10, 1913. Serial No. 772,922. Term of patent 14 years.

To all whom it may concern:

Be it known that I, THOMAS W. MILLER, a citizen of the United States, residing at Ashland, in the county of Ashland and State of Ohio, have invented a new, original, and ornamental Design for Bathing-Caps, of which the following is a specification, reference being had to the accompanying drawing, forming part thereof.

The figure is a perspective view of a bathing cap, showing my new design.

A feature particularly relied on is the peculiar ornamental configuration produced at the point where the puckering of the cap occurs.

I claim:

The ornamental design for a bathing cap, as shown and described.

THOMAS W. MILLER.
